UNITED STATES PATENT OFFICE.

EDWARD H. BINNS AND RALPH H. BINNS, OF PITTSBURGH, PENNSYLVANIA.

TAB OR FINGER PIECE.

Application filed May 15, 1924. Serial No. 713,504.

To all whom it may concern:

Be it known that we, EDWARD H. BINNS and RALPH H. BINNS, citizens of the United States, and residents of Pittsburgh, county 5 of Allegheny, and State of Pennsylvania, have invented certain new and useful Improvements in Tabs or Finger Pieces.

The present invention consists of an improved tab or finger piece for attachment 10 to a bound book of leaves. A rigid plate, preferably of sheet metal, is formed of oblong shape with a longitudinal slot through which some of the leaves of the book may be threaded and having one or more 15 shoulders projecting into the slot and adapted to engage the binding of the book of leaves for positioning the tab or finger piece at the binding edge thereof.

The improved tab or finger piece is particularly useful as an attachment for a small 20 book of leaves mounted in a protecting pocket, in which case the tab or finger piece will project beyond the binding edge of the book and the open edge of the pocket to afford a convenient finger hold for removing 25 the book from its pocket.

One use of the improved tab or finger piece is as an attachment to the ordinary 30 book of stamps issued by the Government, the tab being easily applied to the book and changed from an old book to a new book when desired.

In order that the invention may be fully 35 understood it will first be described with reference to the accompanying drawings and afterwards pointed out more particularly in the annexed claims.

Figure 1 is a perspective view of a book- 40 enclosing pocket with the improved tab projecting therefrom;

Figure 2 is a similar view showing the 45 bound book of leaves with the tab applied thereto;

Figure 3 is a detail sectional view taken 50 through the central plane of the book and showing the improved tab or finger piece in elevation;

Figure 4 is a longitudinal sectional view taken on the line 4—4 of Figure 3;

Figure 5 is a detail perspective view of the tab or finger piece removed from the book;

Figure 6 is a view similar to Figure 3 showing a slight modification; and

Figure 7 is a face view of a tab or finger 55 piece embodying the features of the tabs shown in both Figures 3 and 6.

1 represents a book of leaves bound in any suitable manner such as by means of the wire staples 2. 3 is an opened pocket 60 of leather, or other suitable material, adapted to contain the book of leaves 1. 5 is the improved tab or finger piece formed preferably of a sheet-metal stamping with a longitudinal slot 6 into which project the 65 end shoulders 7. The outer edge of the tab or finger piece is suitably shaped and ornamented to constitute a convenient finger hold.

In mounting the tab or finger piece upon 70 a book of leaves, the leaves are separated approximately in the middle of the book and threaded or passed through the slot 6, and the finger piece passed up over the bound edge of the book of leaves as shown in Figures 1 and 3. In this position the shoulders 7 will be presented adjacent to or in 75 engagement with the outside arms of binding staples 2 as shown particularly in Figure 3, so as to prevent lateral displacement of the finger piece upon the book. 80

In Figure 6 the finger piece 5 is formed with a central inwardly projecting lug or shoulder 8, which when the finger piece is mounted upon the bound edge of the book of leaves will be presented between the adjacent inner legs of the staples 2 and by its 85 engagement therewith prevent the displacement of the finger piece upon the book of leaves.

In Figure 7 the finger piece 5 is shown 90 with both forms of inwardly presented lugs or shoulders 7, 8.

We claim:

1. The combination with a book of leaves bound adjacent one edge, of a slotted rigid plate inserted between said leaves and embracing the binding thereof and projecting beyond said bound edge to constitute a tab or finger piece.

2. The combination with a book of leaves bound adjacent one edge, of a slotted sheet-metal plate inserted between and embracing the bound edge of said leaves and projecting beyond said bound edge to constitute 100 a tab or finger piece.

3. The combination with a book of leaves bound adjacent one edge, and a pocket enclosing said leaves, of a slotted sheet-metal 105

- plate inserted between said leaves and embracing the binding thereof and projecting beyond said bound edge and pocket to constitute a tab or finger piece.
- 5 4. The combination with a book of leaves bound adjacent one edge, of a sheet-metal plate formed with a slot defined by a shouldered wall, some of said leaves being threaded through the slot of said plate to 10 present the plate between the leaves at the binding edge and a shoulder in engagement with the binding, and the edge of said plate projecting beyond said bound edge in the form of a tab or finger piece.
- 15 5. An attachment for a bound book of leaves consisting of a flat sheet-metal plate formed with a slot to receive leaves and a shoulder projecting into the slot to engage the binding.
- 20 6. A tab or finger piece for a bound book of leaves consisting of a slotted sheet-metal plate adapted to be inserted between the leaves to embrace the binding thereof and formed with a lug or shoulder projecting into the slot in position to engage the binding of the leaves.
7. A tab or finger piece for a bound book of leaves, comprising a flat sheet-metal plate formed with a slot to receive the leaves and embrace the binding thereof, and a lug or shoulder projecting into the slot in position to engage the binding to prevent displacement of the tab or finger piece.
8. The combination with a book of leaves bound by wire staples adjacent to one edge, of a tab or finger-piece formed of a flat sheet-metal plate slotted to be passed over the leaves into position to embrace the binding thereof, and a lug or shoulder projecting into the slot in engagement with the wire staple binding, said plate projecting beyond the bound edge of the leaves to constitute a tab or finger piece.

EDWARD H. BINNS.
